SCORING MECHANISM

Julius M. Seidel, Brooklyn, N. Y.

Application August 22, 1945, Serial No. 611,958

1 Claim. (Cl. 235—144)

This invention relates to a scoring mechanism for game apparatus and pertains more especially to a resetting device for such mechanism. While the invention is not limited to any particular field of use it is nicely adapted for use in connection with the scoring mechanism of the bowling game commonly known as "skeeball."

An object of this invention is an improved and efficient resetting device in which the applied operating force is always the same and the possibility of injury to the apparatus by the application of excessive operating force is effectively prevented.

Other objects, novel features and advantages of this invention will be apparent from the following specification and accompanying drawings wherein Fig. 1 is a side elevation of a game apparatus equipped with scoring mechanism embodying the resetting device embodying the invention. Fig. 2 is a side elevation of the scoring mechanism. Fig. 3 is a perspective view of the operating means for the resetting device. Fig. 4 is a fragmentary side elevation of the scoring mechanism looking into Fig. 2 from the left. Fig. 5 is a similar view looking into Fig. 2 from the right. Figs. 6 and 7 are fragmentary side elevations showing different positions assumed by the resetting device in its cycle of operations. In Fig. 1 **10** represents a game apparatus commonly known as "skeeball." This apparatus is provided with a lever **11** which releases the balls which are used in playing the game and through which resetting of the scoring mechanism is effected. A link **12** connects the lever **11** with an arm **13** rotatably supported by the shaft **14**, a spring **15** tending to return the lever **11**, link **12** and arm **13** to the position shown in Fig. 1 after the same had been moved from such position. A second arm **16** is fixed to the shaft **14** and a third arm **17** is also fixed to the shaft **14**. A spring **18** exerts a pull on the arm **17** tending to return it to the position shown in Fig. 1 after movement from such position and a dashpot **19** is associated with the arm **17** for cushioning the return of the arm **17** to normal position under the influence of the spring **18**. The link **20** leads from the arm **17** to the resetting means later to be described. A pull on the lever **11** moves the arm **13** into contact with the arm **16** thereby effecting rotation of the shaft **14** and movement of the arm **17** to the left against the action of the spring **18**. Upon release of the handle **11** the spring **15** returns the arm **13** to original position and the spring **18** returns the arm **17** to its original position. The upward force applied to the link **20** is thus always the same

and is determined by the characteristics of the spring **18** and the dashpot **19**.

A rotary scoring mechanism **21** is suitably mounted on the apparatus **10** and consists, generally speaking, of a squirrel cage having leaves **22** pivoted to the cage bars and bearing appropriate numbers which drop from a fixed rest **23** as the squirrel cage is rotated. These leaves bear suitable markings or numbers to indicate, one at a time through a suitable opening, the score made by the player of the game. At one end of the squirrel cage are provided a plurality of pins **24** corresponding in number with the number of leaves **22** and a pawl **25** is provided for engaging the pins **24** to advance the member **21**. A link **26** connects the pawl **25** with suitable actuating mechanism which constitutes no part of this invention and may be any of the mechanisms now used for this purpose. The pawl **25** is carried by one end of a lever **27** which is pivoted on a stud **28** and is provided with a projection **29** adapted to be arranged between successive pins **24** to prevent accidental rotation of the member **21**. A spring **30** tends to hold the lever **27** and pawl **25** in the position shown in Fig. 2. A dog **31** also pivoted on the stud **28** is provided with a counterweight **32** to maintain its right end in contact with the pins **24** to prevent clockwise rotation of the member **21**.
30 A resetting finger **33** is mounted for rotation relative to the member **21** and is connected to the pinion **34** for rotation therewith. A quadrant **35** meshes with the pinion **34** and is rotatably supported by the stud **36**. An arm **37** extending from the quadrant is connected to the link **20**. A dog **38** is mounted on the member **21** for engagement by the finger **33**, the arrangement being such that the dog permits of clockwise movement of the finger **33** past it, but upon counterclockwise movement of the finger **33** remains in the path of movement of the finger. With this arrangement downward pull on the link **20** causes clockwise rotation of the finger **33** without any effect on the member **21**, while upward movement of the link **20** brings the finger **33** into engagement with the dog **38** to effect counterclockwise rotation of the member **21**.
35 The detent **39** is engageable by a pin **40** on member **21** to stop counterclockwise rotation of the member **21** at a zero or completely reset position. This detent **39** is pivoted on the stud **41** and is provided with a pin **42** engaged by cam surface **43** provided on the arm **27a** of the lever **27**. A spring **44** tends to maintain the detent **39** in position to be engaged by the pin **40**. A cam

45 is connected to the quadrant 35 for rotation therewith and a second cam 46 is supported coaxially with the cam 45, but is rotatable independently thereof. In the cam 46 is provided a notch having a shoulder 49 engageable by a pin 48 on the lever 27 to prevent counterclockwise rotation of the cam 46. The working surface of the cam 45 is equal in radius to the right-hand end of cam surface 46 as seen in Fig. 2 but is less in radius than the left-hand thereof and is arranged to engage the pin 48 to move it out of the notch to permit rotation of the cam 46 and a spring 47 connects the cams 45 and 46 so that after the cam 46 is released rotation thereof will be effected by the spring 47 to bring the pin 46a on the cam 46 into engagement with the shoulder 45a on the cam 45. The cam 46 is of less radius adjacent the notch 49 than it is adjacent the other end of its periphery and the working surface of the cam is arranged to move the lever 27 sufficiently that the detent 39 is moved out of the path of the pin 40 while the movement of the lever 27 effected by the cam 45 is insufficient for that purpose.

The operation of the resetting mechanism is as follows: Assume that the member 21 has been advanced to some position other than the zero position shown in Fig. 2 in the course of the operation of the game apparatus with which the mechanism is associated. The dog 38 will then be moved to some position counterclockwise of the position shown. A pull on the resetting lever 11 will effect a downward pull on the link 20, as previously described, with consequent counterclockwise rotation of the quadrant 35 and clockwise movement of the finger 33 through an arc of nearly 540° to the position shown in Fig. 7. The cam 45 is rotated with the quadrant 35 and in its initial period engages the pin 48 to move the same out of the path of the shoulder 47 of the cam 46 with corresponding movement of the lever 27 (see Fig. 6). As soon as the cam 46 is released the spring 47 causes counterclockwise rotation of the cam 46 with consequent further movement of the lever 27 by reason of the engagement with the pin 48 by the working surface of the cam 46. The movement of the lever 27 effected by the cam 46 is sufficient to move the detent 39 out of the path of the pin 40 through the interaction of the pin 42 and the cam surface 43. The member 21 is now released for counterclockwise movement, all the above described operations having been performed by moving the lever 11 from the position shown in Fig. 1 in full lines to the position shown in the same figure in dotted lines. Upon release of the handle 11, the arm 13 immediately returns to its original position while the arm 17 is returned to its original position under the control of the spring 18 and dashpot 19, as previously described, with corresponding upward movement of the link 20. The upward movement of the link 20 effects

clockwise rotation of the quadrant 35 and counterclockwise rotation of the finger 33 to bring the same into engagement with the dog 38, thereby effecting counterclockwise rotation of the member 21. Likewise, clockwise rotation is effected of the cams 45 and 46 through the engagement of the pin 46a with the shoulder 45a, the relative positions of the cams 45 and 46 being such that the notch 49 is open to receive the pin 48. When the notch 49 comes into register with the pin 48 the lever 27 is operated by the spring 30 to move the pin 48 into the notch 49 and at the same time to release the detent 39 to be moved back into the path of the pin 40 by the spring 44. The design of the various elements just referred to is such that the detent 39 moves into the path of the pin 40 before the member 21 has reached its zero position. Engagement of the pin 40 with the detent 39 stops the member 21 in the zero position, as shown in Fig. 2.

The forward pull on the lever 11 conditions the resetting mechanism and the forward movement of such lever is limited by engagement with the front end of the slot in which it is arranged so that excessive force cannot be applied. The actual resetting of the scoring mechanism is effected by the force developed by the spring 18 and controlled by the dashpot 19 so that the resetting force is always the same and excessive force cannot be applied in the resetting operation.

This application is a refile of applicant's previously allowed application, Serial No. 92,994, filed July 28, 1936.

I claim:

A device of the character described comprising a rotatable member, a rotatable finger coaxial with said member, an oscillatable member geared to said finger, manually operable means for actuating said oscillatable member to effect advance rotation of said finger through an arc of more than 360°, a dog on said rotatable member in the path of said finger, said dog being yieldable to permit passage of said finger upon advance rotation thereof, spring means for actuating said oscillatable member to effect reverse rotation of said finger to initial position, a pin on said rotatable member, a pivoted lever adapted to engage said pin in the zero position of said wheel, a cam connected to said oscillatable member, a notched second cam coaxial with said first cam but rotatable relative thereto, resilient means connecting said cams, a second lever having an operating connection with said first lever, and a cam follower on said second lever adapted to seat in the notch of said second cam, said first cam being effective upon initial movement to lift the follower out of the notch and said second cam being effective to move said first lever into inoperative relation to said pin.

JULIUS M. SEIDEL.
